G. R. RICH.
TAPPET FOR INTERNAL COMBUSTION ENGINES.
APPLICATION FILED FEB. 12, 1917.

1,228,350.

Patented May 29, 1917.

his Atty.

UNITED STATES PATENT OFFICE.

GEORGE R. RICH, OF BATTLE CREEK, MICHIGAN, ASSIGNOR TO RICH STEEL PRODUCTS COMPANY, OF BATTLE CREEK, MICHIGAN, A CORPORATION OF MICHIGAN.

TAPPET FOR INTERNAL-COMBUSTION ENGINES.

1,228,350.

Specification of Letters Patent.

Patented May 29, 1917.

Application filed February 12, 1917. Serial No. 148,272.

To all whom it may concern:

Be it known that I, GEORGE R. RICH, a citizen of the United States, and a resident of Battle Creek, county of Calhoun, and State of Michigan, have invented certain new and useful Improvements in Tappets for Internal-Combustion Engines, of which the following is declared to be a full, clear, and exact description.

This invention relates to tappets for internal combustion engines, and its primary object is to provide an extremely light but strong, substantial and efficient tappet. There is a demand at present for a light tappet for internal combustion engines of the types employed in motor cars, and many efforts have been made to produce a light tappet which shall possess the above mentioned requirements, but to the best of my knowledge and information, no successful results have been obtained thus far. I have produced a tappet, the body of which is constructed of one piece, the head being of comparatively heavy formation, and the stem of very thin, light, tubular formation. The connection with the adjustment bolt or other valve engaging device is secured to the stem by spot welding it thereto. The invention consists in the several novel features herein fully set forth and distinctly pointed out in the claims.

The invention is clearly illustrated in the accompanying drawing, in which:

Figure 1, is a side elevation of a tappet embodying a simple form of the present invention; Fig. 2, is a vertical section thereof taken on the line 2—2 of Fig. 1; Fig. 3, is a side elevation of a tubular, internally screw threaded plug which forms part of the tappet shown in Figs. 1, and 2; and Fig. 4, is a central vertical section of a slightly modified form of the invention.

Referring to said drawing, and first to Figs. 1 to 3, inclusive, which illustrate a simple embodiment of the invention, 10, designates the body portion of the tappet, 11, the adjustment bolt and 12, the jam nut. The body 10, has a tubular stem portion 13, formed on one end with a disk like head 14, integral therewith. The wall of the tubular stem portion may be made very thin, in fact the thickness of the metal may be one thirty-second of an inch or less, because the strain on the tappet is only in a lengthwise direction. To provide for a

connection between the adjustment bolt 11, and tubular stem 13, a plug 15, is permanently secured in the upper open end of the stem. Said plug has a portion 16, which protrudes from the tubular stem portion and is of the same diameter as said stem, and has two oppositely disposed flat faces 16^a, to which a wrench may be applied. Below the protruding portion, the plug has a neck 17, which fits in the upper open end of the stem and is spot welded thereto as at 18. The shoulder 19, formed between the neck and protruding portion of the plug, bears against the extreme end of the stem.

The plug is bored and tapped for the reception of the adjustment bolt 11, and the jam nut 12, is placed on the bolt as usual, and screwed down against the plug to lock the bolt in any position of adjustment.

Preferably the body portion 10, is made from a solid piece of steel, bored out to form the tubular stem, and preferably it is case hardened to provide the hard head, in accordance with practice described in my prior application for patent on tappets, filed September 18, 1916, Serial No. 120,740, upon which Letters Patent were issued February 6, 1917.

The form of the invention illustrated in Figs. 1 to 3 inclusive, is intended for use in internal combustion engines where the cam shaft is below the valves, and the tappets are interposed between the cams and lower ends of the valve stems, in accordance with the practice well known to those skilled in the art to which this invention pertains.

In the modified form illustrated in Fig. 4, the body portion 10^a, is constructed in the same manner as the form shown in Figs. 1 and 2. This form is intended for use in motors employing overhead valve mechanism. In this form the plug 15^a, is drilled to form a socket 20, which is adapted for the reception of a rod or stem of the valve mechanism. The protruding portion may be cylindrical in form, and its reduced portion 17^a, is spot welded to the tubular stem as in the preferred form.

It is readily apparent that by making the wall or shell of the stem portion very thin, the weight of the tappet is reduced materially, thus accomplishing the result desired, and that by providing a thicker walled plug, permanently secured to the stem, suit-

able connections with the adjustment bolt are obtained.

More or less variation of the exact details of construction is possible without departing from the spirit of this invention; I desire, therefore, not to limit myself to the exact forms shown and described, but intend in the following claims to point out all of the invention disclosed herein.

10. I claim as new and desire to secure by Letters Patent:

1. A tappet for internal combustion engines, comprising a body portion consisting of a single piece having a thin walled tubular stem, formed with a disk like head on one end thicker than the wall of the stem, and a plug seated on the open end and permanently secured to said stem.

2. A tappet for internal combustion engines, comprising a one piece body portion consisting of a disk like head portion, and a tubular stem portion, the wall of the stem portion being considerably thinner than the head, and a plug having a portion protruding from the stem, and of the same external diameter as the stem, and having a reduced portion fitting in said stem and welded thereto.

3. A tappet for internal combustion engines, comprising a one piece body portion consisting of a disk like head portion and a

tubular stem portion, the wall of which is considerably thinner than the head, and a centrally bored internally screw threaded plug, having a neck portion located in the 35 open end of the stem and permanently secured thereto, said plug protruding from said stem, and the protruding portion being of the same diameter as the stem and having two oppositely disposed flat surfaces 40 adapted to be grasped by a wrench.

4. A tappet for internal combustion engines, comprising a single piece body portion, consisting of a disk like head and a tubular stem, the wall of which is thinner 45 than the head, and an internally screw threaded, tubular plug, seated on the open end of said stem, and having a reduced portion projecting into the hollow of the stem and welded thereto, the protruding portion 50 being of the same diameter as the stem, and having two flat faces, adapted to be grasped by a wrench, said plug being arranged to receive and hold an adjustment bolt.

5. A tappet for internal combustion engines, comprising a single piece, case hardened, body portion, consisting of a disk like head and a tubular stem, the wall of which is thinner than the head, and a plug seated 55 on the end of said stem and welded thereto. 60

GEORGE R. RICH.
